UNITED STATES PATENT OFFICE.

HENRY A. NICHOLSON, OF ARKLES BAY, AUCKLAND, NEW ZEALAND, ASSIGNOR TO ERNEST A. CRAIG, OF AUCKLAND, NEW ZEALAND.

STEAM GENERATOR.

Application filed May 10, 1919. Serial No. 296,086.

To all whom it may concern:

Be it known that I, HENRY A. NICHOLSON, a citizen of New Zealand, and a subject of the King of Great Britain, residing in Arkles Bay, Auckland, New Zealand, have invented certain new and useful Improvements in Steam Generators, of which the following is a specification.

This invention relates to steam generators of the class set forth in my pending application 284,657, in which water advancing through a single tubular circuit is gradually heated to a high temperature and its conversion into steam completed as it enters the steam drum.

According to the present construction, the flames may pass directly from a fire box of simple type into a chamber which contains a grid of water tubes, the tubes being spaced apart to facilitate heating, and the flames being compelled to follow a zigzag course up through the flame chamber by means of a system of baffle plates, which are inserted between certain rows of tubes. Thus there is provided an inexpensive and simple apparatus for heating the fluid to a pressure higher than that which it is necessary to maintain in the service steam drum.

A reserve of heated water is provided in a drum arranged between the grid and the force pump which supplies the water, as set forth in said application.

The heated fluid is delivered from the grid into a steam drum, which is provided with a converting device, the pressure being preferably reduced about fifty pounds, so that the heated fluid which reaches the drum under high pressure is let into the drum in the form of steam at a lower pressure. The converting device may regulate the pressure of steam in the service drum.

Provision is also made to guard against trouble from too great a pressure being generated in the reserve water drum in case of any difficulty arising in the grid system. This is accomplished by placing a service safety-valve at the delivery side of the apparatus, and a second or special safety valve, set say at 50 to 100 pounds higher pressure than the first, at a point between the reserve water drum and the grid system. The service valve will safeguard the generator under ordinary circumstances; but should steam escape from the second valve, it will give warning that there has occurred

an obstruction to the delivery of highly heated fluid from the grid to the delivery drum. This is evident because the service valve would blow off if the pressure in the delivery drum were above normal, whereas the blowing off of the special valve shows that pressure is excessively above normal in the reserve water drum.

Other features and advantages will hereinafter appear.

In the accompanying drawings,

Figure 1 is a part-sectional side elevation of a steam generator embodying the present improvements in one form.

Figure 2 is an edge elevation of a preferred form of baffle plate for the flames used in the grid chamber of the generator.

Figure 3 is a detail of a pressure-reducing valve used at the inlet of the steam drum.

Figure 4 is a plan of the generator.

Figure 5 is a front elevation of the fire box, one of the doors and door plates being removed to disclose the interior.

Figure 6 is a diagram to show the operation of the apparatus.

Figure 7 is a sectional elevation taken transversely of the flame chamber, showing the arrangement of the grid and baffle plates therein.

The fire box comprises side walls 20, rear wall 21 and top 22, all of which may be of brick; the top being supported by a bridge or crown plate 23. In the front wall 24 of the fire box are arranged vertical frames 25 or plates 25, each having a fuel door 26 and an ash door 27. The fuel rests upon a grate 28.

In the upper part of the rear wall is formed an opening 29, for the passing of flames into a flame chamber, which comprises a front wall 30, a rear wall 31, and side walls 32, 33; the flames passing in a zigzag course through this chamber, to heat the water which is advancing in a set of tubes forming a grid, which will presently be described. The hot gases vent through a chimney 34, having a damper 35. The air is preferably passed through the fuel by forced draft.

The water from which the steam is generated is supplied by a force pump 36, a reserve of water being accumulated in a drum 37, through which the pump communicates by means of a main 38 rising therefrom,

and extending horizontally at 39, said drum being arranged just below the chimney 34, where it is exposed to the outflowing hot gases and heated thereby. Said grid chamber or flame chamber 30, 31, 32, 33 is surmounted by a dome whose walls are indicated at 40, 41, and this water drum is arranged in said dome so that the gas will circulate on all sides thereof, as set forth in my said companion application 284,657. It will be seen at Figure 4 that the drum is connected to the horizontal portion of the supply main 39 by a short branch or fitting 42.

15 While the boiler is steaming, a valve 43 in the pipe 82 is closed, so that all the water that is forced through 39 by the pump enters the hot water drum 37, keeping the latter filled with water.

20 An outlet 44 is placed in the top of the drum, so as to insure that the drum shall keep filled with water. This is evident because if any steam should form in the drum, it must first pass through the outlet 44, permitting water to rise in the drum. In other words, steam cannot be trapped in the drum.

25 The water flows out through a short horizontal pipe 45, and down through a vertical pipe 46 to the middle of a distributor 47, at whose ends are elbows 48 joined to headers 49, 50 at the top of the flame chamber. These headers extend horizontally along the sides of the chamber. From the headers the water flows down through a grid, and 30 is collected at the bottom by means of other horizontal side-headers 51, 52. The ends of the strips 23 and 28 are equipped

35 The grid is composed of vertical sections, each section comprising horizontal transverse tubes 53, through which the water flows down in a zigzag course, as will be understood from Figure 7: the tubes being connected at their rear ends alternately by 40 couplings or vertical tubes or passages 54 provided in vertical headers 55, which may be of the construction set forth in said application 284,657. These grid sections connect alternately with headers 49, 50, the upper tube in each grid section having a 45 coupling 56 opening into header 49 or 50, and the lower tube in the same section having a coupling 57 opening into lower header 51 or 52; the preferred construction being such that the uppermost tube connects with the horizontal distributing header on one side, while the lowest tube connects with the horizontal collecting header on the other side. It will be seen that the water from 50 either distributing header 49 or 50 flows

55 down in a zigzag course through the flame chamber and is collected in one of the bottom headers 51 or 52, at the delivery portion of the generator. The vertical section headers are provided with screw-plugs 58 for

60 clean-out openings formed therein opposite

the ends of the tubes. Each grid section is a unit, being connected at its upper end at one side by flanges 59 to flanges on the upper header, and at the bottom on the other side by flanges 60 bolted to flanges on the bottom header. Adjustable supports in the form of screws 61 may be provided for the remaining corners of each grid section.

65 A system of baffle plates 62, 63, 64, 65, and 66 may be provided for directing the flames in a zigzag path up through the grid chamber; said plates being preferably of corrugated form for strength, as indicated in Figure 2; this form of plate having plain supporting flanges 67 at its ends. These flanges may rest upon lugs 68 provided upon some or all of the vertical headers 55 of the grid sections; the plates being slid horizontally forward into position upon these lugs before the rear wall 31 of the grid chamber is set up.

70 As seen at Figure 1, these baffle plates are all too short to extend from front entirely to the back of the grid chamber. They are set alternately against the front and back walls, so as to leave flame passages at alternate ends. The baffle plates 62, 64, and 66, for example, are set against the front wall, while plates 63 and 65 may be set against the rear wall.

75 At the top of the flame chamber, surmounting the top row of tubes, may be provided a special baffle plate 69, which may be much shorter than the others, to leave a broad opening for the vent of flames and hot gases from the grid chamber.

80 These baffle plates are placed between alternate horizontal rows of tubes as illustrated, the rows of tubes being numerous, and the baffle plates being preferably not so numerous as to interfere with the proper flow of flames and hot gases through the grid chamber.

85 From the collecting headers 51, 52, the heated fluid is delivered through vertical pipes or mains 70, and horizontal pipes 71 and inlets 72, to the ends of a steam drum 73.

90 At each inlet 72 is placed a device whereby the remnant of the fluid which is in water form and which reaches said inlet under high pressure may be converted and enter the drum in the form of steam. At Figure 3 is illustrated one form of converting device, consisting of a valve 74, which may close the inlet or orifice 75 provided in the drum, and may have a horizontal guiding stem 76, pivoted at 77 to the short arm 78 of an elbow lever pivoted at 79 upon a fixture 80 within the drum, and carrying an adjustable weight 81; said weight being preferably adjusted to such a point that the pressure of steam within the drum is regulated to fifty pounds less than that of the heated fluid in the delivery main 71. The

steam drum is in communication with only the delivery end of the system of water piping, which system includes the grid.

When the generator is being heated up, 5 the valve 43 is opened, thus permitting circulation of water as it becomes warmed. At this time, the pump is not working. The heated water rises to the top of the grid system, and the cooler water flows to the 10 bottom of the apparatus, so that a circulation is set up by the heated water rising in the grid. The coolest water reaches the lower headers 51 and 52, and upon becoming heated rises in the grid, flowing through 15 the distributor 47 to the drum 37, whence it may flow down through the main 82 (containing said valve 43), down through pipes 71, 70 to the bottom of the system. This circulation may continue until steam forms, 20 whereupon the valve 43 may be closed, and the pump 36 may be started. The pump may of course be operated by steam now derived from the generator. Heat is supplied as the water progresses in its single 25 passage through the generator, until the temperature of the water far exceeds 212° F. The time spent by any portion of water in the generator is only enough to enable it to acquire the desired degree of heat 30 once. The smallness of the heating surface is rendered possible by the fact that the water does not circulate around and around, but is heated only once, and as soon as sufficiently heated is used. The fluid is forced 35 through the system at such a rate that it will acquire the maximum of heat just as it is about at the lowest point. The constant forced flow of fluid tends towards uniformity of heat in the water-pipe system, and hence to prevent excessive heat at 40 any point. By means of the grid and its distributing headers, the flow of fluid is split up into fine streams, so as to expose it intimately to the flames, and to heat it 45 quickly, so that it may not remain in the generator many minutes, and will not absorb more heat than necessary to produce the required delivery of steam.

In the steam delivery main leading from 50 steam drum is arranged a service safety valve 82^a, which may be set to keep the pressure in the steam drum 73 within normal limits; while in a pipe 83 let into the main 46 between the water-reserve drum 37 and the grid system may be arranged an 55 emergency safety valve 84, set at say 50 or 100 pounds higher pressure than the service valve 82^a. Under ordinary conditions the generator will be amply protected by the service valve 82^a; but if from any cause there should be a checking of the flow of water through the grid system, so that the pressure rises unduly high in the water reserve drum 37, the emergency safety valve 60 84 will blow off. This notifies the engineer

that there is normal or less than normal pressure at the delivery portion of the generator, and pressure much in excess of normal at another portion thereof. He will immediately stop the pump 36, and the reserve of hot water in the drum 37 will enable the generator to continue delivering steam for a time, until the trouble can be ascertained and remedied. If necessary, the valve 43 may be opened after the pump is 70 stopped, permitting the water to keep flowing idly through the system, obviating the liability of the overheating of the tubes or pipes at any point. This circulation will afford opportunity for the fire to be drawn or other precautions taken. If desired, a back-pressure valve 85 may be arranged in main 39, to prevent liability of heating of the pump 36 by hot water or steam.

Variations may be resorted to within the scope of the invention, and portions of the improvements may be used without others.

Having thus described my invention, I claim:

1. A steam boiler system comprising a furnace, a grid of downwardly extending tubes therein, a pump for forcing water into the upper entrance of said grid, a steam drum above the grid of tubes into which the tubes deliver, said drum having a steam outlet and normally having communication with the grid of tubes only at their ends furthest from the pump whereby the same water can pass only once through the tubes, and said communication means comprising means for reducing the pressure of the fluid as it passes from the grid into the drum. 90

2. A boiler system comprising a grid of downwardly extending tubes, a pump for pumping water into the upper entrance end of the tubes, means for heating the tubes to convert the water into steam and a steam drum within the furnace above said tubes and normally having communication only with the exit ends of the tubes, said drum having a steam outlet, and said communication having thereon means for reducing the pressure of the fluid as it passes from the grid into the drum. 105

3. A boiler system comprising a furnace, a grid of tubes zig-zagging back and forth in the furnace from top to bottom thereof, a pump for pumping water into the upper entrance ends of the tubes, and a steam drum within the furnace and normally having communication only with the exit ends of said grid of tubes, whereby the same water can pass only once through the tubes, said drum having a steam outlet, and said communication having therein means for reducing the pressure of the fluid as it passes from the grid into the drum. 115

4. A boiler system comprising a furnace, a grid of tubes extending from the upper part thereof to the bottom of the furnace, a 120

125

130

5 pump for pumping water into the entrance ends of the tubes, a header into which said tubes discharge, and a steam drum normally having communication only with the said header, there being a pressure reducing means between the header and the steam drum.

10 5. A boiler system comprising a furnace, a header thereon, a grid of tubes zig-zagging back and forth from the said header to the bottom of the furnace, means for forcing water into the header and down said tubes, a steam drum in the top of the furnace normally having communication only with 15 the exit ends of the tubes, and a pressure reducing means between the drum and the tubes.

20 6. A boiler system comprising a furnace, headers in the upper portion of the furnace, grids of tubes in the furnace extending from said headers downwardly, a pump for pumping water into the headers and tubes, headers in the lower portion of the furnace into which the tubes discharge, a steam drum 25 into which the lower headers discharge, and pressure reducing means between the lower headers and said steam drum.

7. A boiler system comprising a furnace, a water drum and a steam drum both inside the furnace and a grid of tubes having their 30 entrance ends connected with the water drum and their discharge ends with the steam drum and normally forming the only communication between said drums, baffle plates in the furnace between portions of 35 the tubes, a pump for pumping water into the water drum, a steam exit for the steam drum extending outside the furnace, and pressure reducing means in the said connections between said tubes and said steam 40 drum.

8. A boiler system comprising a furnace, a steam drum, a water drum and water headers inside the upper portions of the furnace, connections between the water drum 45 and headers, a grid of tubes leading from the headers downwardly through the furnace and discharging in the steam drum, said steam drum having a steam outlet extending outside the furnace and pressure 50 reducing means governing the said discharge from said tubes into said steam drum.

HENRY A. NICHOLSON.
